UNITED STATES PATENT OFFICE.

JOE KOVAR, OF COUPLAND, TEXAS.

INCUBATOR.

1,392,177.

Specification of Letters Patent. Patented Sept. 27, 1921.

Application filed October 25, 1920. Serial No. 419,859.

To all whom it may concern:

Be it known that I, JOE KOVAR, a citizen of the United States, and resident of Coupland, in the county of Williamson and State of Texas, have invented a new and Improved Incubator, of which the following is a full, clear, and exact description.

My invention relates to an automatic heat regulating unit, and more particularly a device of this nature primarily intended to be associated with an incubator.

In connection with incubators, it is a well appreciated fact that considerable difficulty has been experienced in providing a heating unit which might be entirely automatic in operation, and which would permit of a minimum of variation of heat within the incubator, and in which any tendency on the part of the heating medium to cause the temperature to rise or drop beyond a predetermined point would be materially counteracted.

With this in view, I have constructed a heating system more particularly intended for use in connection with incubators, but not necessarily limited to this adaption, and by means of which the temperature of the incubator or other device with which the system is associated, will be constantly maintained at a predetermined point.

A further object of my invention, is the construction of a device of this nature which shall be extremely simple in construction, and hence economical to manufacture, as well as to operate.

A still further object of my invention is the construction of a heating system of the type specified which shall be entirely automatic in operation, so that a minimum of attention is required.

Further objects of my invention will appear in the annexed specification and drawings, which latter represent one practical embodiment of my invention, and in which Figure 1 is a side view of an incubator having a heating system constructed in accordance with my invention applied thereto.

Fig. 2 is a fragmentary sectional view taken along the line 2-2 of Fig. 1.

Fig. 3 is a side view of certain of the parts forming the system.

Fig. 4 is a sectional side view taken along the line 4-4 of Fig. 5, and

Fig. 5 is a plan view of the device with the top removed.

In these views the reference numeral 10 indicates the side walls and base of the incubator, which may be properly heat insulated, as at 11, and which are supported by suitable legs, as at 12.

A top, or lid of any convenient construction is associated with the incubator, thus providing a top conveniently also embracing a heat insulated portion 13, provided with a sight opening 14, and preferably a layer of transparent material 15, below said top, and detached therefrom so that the top may be removed without exposing the interior of the incubator or other device, to a sudden chill.

The incubator, however, preferably includes a centrally extending partition 16 formed with an opening 17, thus providing an incubating space 18 and brooding space 19, the chicks, subsequent to their being hatched, dropping through the opening 17 into the brooding space 19.

My heating system now conveniently includes, a radiating pipe or conduit 20, preferably disposed adjacent the upper side edges of the incubating space in which position, it is supported by any suitable brackets 21.

The pipe 20 is preferably formed with an extended portions 22, which is adapted to directly over-lie a lamp or other suitable heating element 23, so that the fluid within this conduit may be properly heated. An inlet, in the form of a trough 24 is provided at one point in the conduit 20, an outlet pipe 25 being conveniently positioned at a point substantially opposite the trough 24.

It is now to be noted that the trough 24 is preferably at a point slightly higher than the conduit so that water introduced into the trough will readily flow into the conduit. It will also be seen that a bracket, or other supporting member 26 is conveniently associated with the outlet pipe 25 to retain this outlet pipe at a height corresponding to the height of the fluid to be maintained within the conduit 20. Thus upon the introduction of water into the trough 24, a proportionate amount of water will flow from the outlet pipe 25 and into a convenient receptacle 27.

A thermostat, of any convenient type, 28, is preferably positioned within the incubator chamber 18, and serves to operate a lever 29 pivotally mounted as at 30. A second lever 31 is disposed beyond the outer

face of one of the side walls of the incubator, and adjacent the thermostat positioned within the same, and this latter lever is rockingly retained in position by means of a forked bracket 32, vertically adjustable as at 33 for a purpose hereinafter more fully specified, to which the lever 31 is rockingly secured as at 34.

It will be noted that the lever 31 extends to both sides of its point of support 34, and a counter-weight 35 is conveniently associated with this lever, adjacent one of its ends. The opposite end of the lever 31 extends to a point adjacent and above the inlet trough 24, it being noted that the outer end of the lever 29 conveniently engages the lever 31, as at 36, thus permitting the thermostat 28 to move the same, a stop 37 being utilized to limit the upward movement of the lever 31.

A source of water supply, such as a flask 38 is movably supported as at 39, upon a bracket 40 positioned adjacent the trough 24, it being noted that the flask 38 conveniently cooperates and feeds a "constant level" trough 41 of any conventional type, from which a flexible feeding pipe 42 extends, it being noted, as has been clearly indicated in Fig. 8, that the outer end of the lever 31 supports the outer end of this pipe.

Now in operation, it will be understood, assuming that the heat has risen above the temperature at which the parts have been adjusted to operate, that the thermostat 28 will expand, thus depressing the outer end of the lever 29 associated therewith. This action will result, by virtue of the connection 36, in a depressing of the lever 31 in turn permitting the feeding pipe 42 to swing downwardly above the trough 24 to a horizontal level, at which the trough 41 will feed through the pipe 42, into the trough 24 consequently introducing cold water into the conduit 20.

This obviously will instantly lower the temperature, it being noted, as has been aforescribed, that an amount of hot water, equal to the amount of cold water introduced into the conduit will be displaced therefrom through the outlet pipe 25. The heating element 23 will continue to heat the fluid within the conduit 20. It will be obvious that upon the temperature falling below the degree which is to be maintained, that the introduction of cold water into the conduit will cease, due to the fact that the thermostat

28 will become contracted, thus raising the outer end of the lever 29, this lever raising the lever 31, and consequently the feed pipe 42.

It will be obvious that the temperature which is to be maintained may be adjusted by virtue of the bracket 32, and the support 30. These two members permit of the adjustment of the height of the pivot of the lever 31, together with the height of the feeding pipe 42, which will obviously produce the result desired.

From the foregoing it will be understood that I have constructed a heating medium more particularly adapted for use in connection with an incubator, but not necessarily limited to this adaption, and in which numerous modifications of structure might readily be resorted to without in the least departing from the spirit of my invention, which I claim as;

1. A heating system, including a conduit, a thermostat, means for heating fluid without the conduit, a manually operable overflow pipe connected with said conduit, an intake trough connected with said conduit, a second trough, a reservoir adapted to maintain fluid at a constant level in the second trough, a flexible pipe extending from said second trough and having its outer end overlying said intake trough, a thermostat lever connected to and moved by said thermostat, a second lever, and means for pivotally mounting said second lever, said first named lever being connected with said second lever, and controlling the movement thereof, said second lever contacting with the flexible pipe, whereby the latter will be moved proportionate to the degree of movement of the thermostat.

2. In a heating system, a liquid conduit, means for heating the liquid of the conduit, an intake trough communicating with the conduit, a cold water receptacle having a flexible tube extending above said trough, a thermostat, a pivoted lever operated by the thermostat, an adjustable support, a second lever pivoted intermediate of its ends in the said support and with which the free end of the first lever has a loose connection adjacent its pivot, one end of the second lever having a weight thereon and its other end extending below and in engagement with the pipe of the receptacle, and means for limiting the upward movement of said second lever.

JOE KOVAR.
